PUMPING DEVICE

George T. Humphrey, Dallas, Tex., assignor to
Republic Supply Company, Houston, Tex.

Application February 17, 1936, Serial No. 64,239

3 Claims. (Cl. 74—103)

This invention relates to new and useful improvements in pumping devices.

One object of the invention is to provide an improved pumping device which is so constructed as to provide a positive vertical, or straight line lift of the pump rods.

An important object of the invention is to provide an improved device for pumping wells including a pivoted walking beam which is arranged to swing to raise and lower the pump rods, with means for moving the pivot of said beam in a horizontal plane simultaneously with the swinging of the beam, whereby the end of said beam travels in a vertical line during its swing.

Another object of the invention is to provide an improved pumping device having a walking beam fulcrumed in a bearing which is movable in a horizontal plane, and means for guiding and controlling the movement of the bearing, whereby the end of the beam is moved in an absolutely vertical or straight line.

A further object of the invention is to provide an improved pumping device wherein the walking beam is full-floating which permits the beam to be moved laterally during its swing, such lateral movement of the beam compensating the arcuate swing of the beam to cause the end of the beam to travel in an absolutely vertical line.

Still another object of the invention is to provide an improved pumping device including a walking beam which is so mounted that it may be readily removed from its support by merely disconnecting the pump rods and the actuating pitman therefrom, without disassembling the bearing in which said beam is fulcrumed; the assembling of the unit being as readily and easily accomplished.

A further object of the invention is to provide an improved mounting for a walking beam which is arranged so that the beam may be moved completely out of the way of the pumping rods of the well by merely disconnecting the rods and without disconnecting the actuating pitman at the opposite end of the beam.

Another object of the invention is to provide an improved walking beam mounting wherein the beam may be moved laterally a limited distance in a horizontal plane, whereby the end of the beam may automatically adjust or align itself vertically with the pump rods.

A construction designed to carry out the invention will be hereinafter described, together with other features of the invention.

The invention will be more readily understood from a reading of the following specification and

by reference to the accompanying drawings, in which an example of the invention is shown, and wherein:

Figure 1 is a side elevation of a pumping unit, constructed in accordance with the invention, 5

Figure 2 is an enlarged view of one end of the walking beam and its mounting.

Figure 3 is a transverse, vertical sectional view, taken on the line 3—3 of Figure 1.

Figure 4 is a longitudinal, sectional view, taken 10 through the pivot bearing of the beam.

Figure 5 is a transverse, vertical, sectional view, taken on the line 5—5 of Figure 1.

Figure 6 is a partial side elevation of a modified form of the invention, 15

Figure 7 is a view, similar to Figure 2 of still another form of the invention, and

Figure 8 is a horizontal, cross-sectional view, taken on the line 8—8 of Figure 7.

In the drawings, the numeral 10 designates a 20 base on which a Samson post, or other support 11 is mounted. The post is shown as constructed of four angular inclined legs 12 connected and braced by suitable angular members 13. The structural members of the post may be welded, 25 bolted, or otherwise suitably secured together to form a rigid structure. It is noted, however, that the construction of the post is subject to variation and the invention is not to be limited to any particular type of post.

Near the upper end of the post, a pair of parallel angle bars or rails 14 are secured to the inner sides of the legs 12. As is clearly shown in Figures 2 and 3, these angle bars are located in the same horizontal plane and have their horizontal flanges 14' directed inwardly. The length of these bars is such that their ends extend beyond the post on either side thereof. A longitudinal walking beam 15 is located between the upper end of the legs 12 of the post and this beam is supported on the horizontal angle bars 14. It is noted that the space between the legs of the post wherein the beam is located is slightly larger than the width of said beam (Figure 3).

The beam is shown as the usual I-beam and is 45 provided with a bearing 16 at its mid-portion. This bearing is fastened to the underside of the beam and a transverse pin 17 extends through the bearing, projecting at each end. Flanged wheels 18 are fastened to the extended outer ends of the 50 pin and these wheels engage the angle bars 14. Thus, it will be seen that the bars 14 form a track and the flanged wheels riding thereon permit the beam 15 to move horizontally the length of said bars. It is noted that a clearance 19 (Figure 3) 55

is provided between the outer face of each wheel and the vertical flange of each angle bar 14, whereby the entire beam may be moved laterally a limited distance between the bars 14. It is 5 pointed out that when the wheels are resting on the track, the top of the beam extends upwardly beyond the upper end of the legs 12 of the post.

It will be obvious that the beam cannot only move in a horizontal path due to the wheels 10 riding on the track, but also the ends of the beam may be swung in a vertical plane on the pin 17, said pin serving as a fulcrum. One end 15 20 of the beam, which for the sake of clarity will be referred to as to the outer end, is provided with a hanger 21, on which the upper end of the pump rods 22 are pivoted. The lower ends of the rods extend downwardly into the well, and as the beam is swung, said rods are reciprocated vertically in the well. It is noted that when the beam 20 is in a horizontal position (full lines Figures 1 and 2), the pivot point of the rods in the hanger is in horizontal alignment with the fulcrum point of the beam, which is the pin 17.

For swinging the beam to reciprocate the rods 25 22, the opposite end 23 of the beam, hereinafter referred to as the inner end, has the upper end of an actuating pitman 24 pivoted thereto. The lower end of the pitman is pivoted to the outer end of a crank arm 25 which is connected with 30 and rotated by a motor 26, or other suitable power source. As the crank rotates, the beam is swung in a vertical plane on the pin 17, whereby the pump rods 22 are reciprocated in the well.

Heretofore, it has been the general practice to 35 rigidly secure the pin or bearing, on which the beam is fulcrumed, to the Samson post 11. With this fulcrum point of the beam fixed, it is obvious that when the beam is swung, the outer end 20 of the beam which carries the rods 22, travels 40 in an arc. This arcuate travel of the end of the beam causes bending of the pump rods, resulting in breakage and other disadvantages.

As above explained, the fulcrum point of the beam is not fixed but is movable due to the 45 wheels 18, which are carried by the pivot pin 17, riding on the track formed by the angle bars 14. Thus, as the beam is swung so that the outer end of the beam moves upwardly in an arcuate path, it will be obvious that a simultaneous movement or shifting of the fulcrum point of said beam will compensate such arcuate movement which will cause the end of the beam to travel 50 in an absolutely vertical path, which imparts a vertical or straight line lift to the pump rods 22.

55 For limiting and guiding the movement or shifting of the pivot pin 17, to shift the fulcrum point of the beam as the same is swung, a pair of arcuate guide cams or shoes 27 are provided. These arcuate guide shoes are positioned, one on 60 each side of the beam, and each shoe is provided with upper and lower ears 28 on its inner side (Figure 2). The lower ear of each shoe is arranged to be fastened by bolts 29, to the forward or outer end of one of the angle bars 14 of the 65 track. A suitable brace bracket 30 may be welded to the extreme lower end of each guide shoe and the bracket is adapted to be secured by bolts 31 to the underside of the angle bar 14 to further fasten the guide in position. The upper ear 28 70 of each shoe is arranged to be bolted by bolts 32 to the forward extended end of horizontal angle bars 33 which are secured to, and brace the upper end of the legs 12 of the post.

75 As is clearly shown in Figure 5, the arcuate guide shoes 27 extend vertically, one on each side

of the beam 15. A bearing 34 is secured to the underside of the beam and a transverse pin 35 is journaled therein. The outer ends of this pin carry guide rollers 36 which are arranged to ride on the arcuate surface of the guide shoes 27. 5 When the beam 15 is in a horizontal position, as shown in full lines in Figures 1 and 2, the center of the pin 35 is in horizontal alignment with the center of the pin 17, which is the fulcrum point of the beam, and also with the center of the 10 pivot point of the upper end of the pump rods 22.

In operation, assuming the beam to be in a horizontal position as shown in Figure 2, the rollers 36 are located at substantially mid-height of the arcuate guide shoes 27. The hanger 21 on 15 the outer end of the beam is in vertical alignment over the well hole and the wheels 18 and pivot pin 17 of the beam are at substantially the midportion of the track. As the pitman 24 moves downwardly due to the rotation of the crank 25, the 20 inner end 23 of the beam is pulled downwardly 25 causing the beam to swing on the pin 17. At the same time that the pitman is exerting a downward pull on the inner end of the beam, it will also tend to move the beam and the pivot pin 17 25 carried thereby inwardly or toward the pitman. This will assure the rollers 26 positively remaining in engagement with the arcuate guide shoes 27.

As soon as the inner end of the pitman starts 30 to move downwardly, the outer end thereof begins its upward swing. If the pivot pin 17 were fixed, then this upward swing of this end of the beam would be arcuate. But this pivot is free to travel on the track, and therefore, as the upward swing 35 of the outer end of the beam commences, the guide rollers 36 carried by the beam 15, travel upwardly on the face of the arcuate guide shoes 27. Due to the curve of said shoes, it will be seen that as said rollers move upwardly along 40 the shoes, the beam 15, which carries the guide rollers, is moved outwardly. Movement of the beam will, of course, cause a movement of the wheels 18 along the track to cause the pivot pin 17 to be shifted horizontally, whereby the fulcrum point of the beam is shifted or moved in a 45 horizontal plane. The curvature of the arcuate guide shoes 27 is such that the fulcrum point of the beam is shifted a proper distance so as to maintain the travel of the outer end of the beam 50 in a vertical path. It is noted that the arcuate shoes engaged by the rollers permit a gradual shifting of the fulcrum point of the beam, the shifting occurring simultaneously with the swing 55 of the beam. Since the supporting wheels 18 travel along the horizontal track formed by the angle bars 14, the fulcrum point of the beam, which is the pin 17, moves in an absolutely horizontal plane and irrespective of the position of the 60 ends of the beam, will never vary from its horizontal path.

On the downswing of the outer end of the beam, the guide rollers 36 will travel downwardly on the arcuate guide shoes 27 and will shift the fulcrum point exactly as described above, whereby at all 65 times, the outer end of the beam travels in an absolutely vertical line to reciprocate the pump rods in a straight line. Thus, it will be seen that the fulcrum point of the beam is shifted in a horizontal plane simultaneously with the swing 70 of the beam, thereby causing the outer end of the beam to travel in a vertical path, instead of in an arcuate path as is the case when the fulcrum point of the beam is fixed. It is pointed out that due to the slight clearance 19 between the face 75

of the wheels 18 and the angle bars 14, the beam may undergo a limited lateral movement so that it will automatically align itself vertically with the pump rods 22.

5 The structure disclosed in the drawings not only provides a straight line lift for the pump rods 22 but also has other advantages. It is obvious that by unhooking the pump rods 22 from the hanger 21 and disconnecting the pitman 24, 10 the entire beam 15 may be lifted upwardly from between the legs 12 of the post and thereby removal of the beam may be readily accomplished. The device may be reassembled with the same ease. Further, if it is not desired to remove the 15 beam entirely from the post but merely to move the outer end 20 of the beam out of alignment with the pump rods 22, it is only necessary to disengage the pump rods from the hanger and remove the rollers 36 and pin 35 (Figure 5) after 20 which the beam may be moved rearwardly on the track so that the outer end of said beam is moved out of vertical alignment with the rods 22. It is noted that it is not necessary to disconnect the 25 pitman. If for any reason, the arcuate guide shoes 27 are to be removed, the unfastening of the bolts 29, 31 and 32 will permit such removal.

In Figure 6, a modified form of the invention is shown. In this form, instead of the single arcuate shoe 27 on each side of the beam, a double 30 arcuate guide shoe 37 is provided. These double shoes are mounted on the angle bars 14 and 33 exactly as is the single shoe. The guide rollers 36 engage between the shoes and thus any possibility of the rollers disengaging the guide 35 surface of the shoes, is eliminated. The operation of this form is exactly as the first form.

In Figures 7 and 8, still another form of the invention is shown. In this form, the arcuate guide shoes 27 and rollers 36 are omitted. In 40 place of these shoes and rollers, a guide yoke 40 is provided. This yoke has one end pivotally mounted in a bearing 41 fastened to the underside of the end 23 of the beam 15. The other end of the yoke is pivoted in bearings 42 secured on the 45 inner ends of the angle bars 14. The pivot points of the yoke and of the pin 17 of the beam are in horizontal alignment when the beam is in a horizontal position, as shown by full lines in Figure 7.

50 When the pitman 24 is actuated to swing the beam, it will be obvious that the yoke 40 which has one end pivotally attached to the beam will also be swung. Since the opposite end of the yoke is pivoted to a fixed point, the end of the yoke 55 which is fastened to the beam travels in an arc (Figure 7). The arcuate travel of the end of the

yoke will cause a movement of the beam on the track, whereby the fulcrum point of the beam is shifted in a horizontal plane, thereby causing the outer end of the beam which carries the pump rods to travel in a vertical line.

5 In all the forms shown, it is noted that the shifting of the fulcrum point of the beam occurs gradually. This gradual shifting also takes place simultaneously with the swing of the beam, and due to the provision of the track, the pivot pin 17 10 moves in an absolute horizontal plane. Said pin remains in such plane regardless of the position of the ends of the beam 15.

What I claim and desire to secure by Letters Patent, is:

1. A pumping device including, a support, a walking beam, a pivotal mounting carried by the beam and mounted to move transversely of its axis in a fixed horizontal plane in the support, an arcuate guide shoe carried by the support, and a 20 guide roller fastened to the beam and engaging the shoe, whereby when the beam is swung on its pivot the roller riding against the arcuate shoe will move the beam longitudinally to shift the pivotal mounting on said support. 25

2. A pumping device including, a support having a horizontal track, a walking beam, a pivotal mounting carried by the beam and including a roller supported on the track, an arcuate guide shoe carried by the support, and a guide roller 30 fastened to the beam and engaging the shoe, whereby when the beam is swung on its pivot the roller riding against the arcuate shoe will move the beam longitudinally to shift the pivotal mounting on said track with its axis in a fixed 35 horizontal plane.

3. A pumping device including, a support having a spaced pair of horizontal tracks, a walking beam having a transverse pivotal mounting on its underside at its midportion including an axle 40 having rollers at its ends supported on said tracks, said beam having provision at one end for the pivotal attachment of a pump rod and at its opposite end for the application of operating power to rock the beam to lift the pump rod, and 45 means for moving the beam longitudinally towards the pump rod when it is rocked, said means including curved shoes mounted on said support at the ends of said tracks, and rollers mounted on opposite sides of the beam and engaging said 50 shoes, whereby the beam-supporting rollers travel on said tracks and the pivotal axis of the beam is shifted in a straight line in a fixed horizontal plane and the pump rod moves in a fixed straight vertical line. 55

GEORGE T. HUMPHREY.
